United States Patent Office.

OTIS W. STEARNS, OF LEBANON, NEW HAMPSHIRE.

Letters Patent No. 66,409, dated July 2, 1867.

IMPROVEMENT IN WOOD-BENDING MACHINES.

The Schedule referred to in these Letters Patent and making part of the same.

TO ALL WHOM IT MAY CONCERN:

Be it known that I, OTIS W. STEARNS, of Lebanon, in the county of Grafton, and State of New Hampshire, have invented a new and improved Machine for Bending Scythe-Snaths; and I do hereby declare that the following is a full, clear, and exact description thereof, which will enable others skilled in the art to make and use the same, reference being had to the accompanying drawings, forming part of this specification, in which—

Figure 1, sheet 1, is a plan or top view of my invention when the machine is in position before bending the scythe-snath.

Figure 2, sheet 2, is a horizontal section taken in the plane of the line x x , Figure 3, when the machine is in position after the snath is bent.

Figure 3, sheet 3, is a vertical transverse section taken in the line y y , fig. 2.
Similar letters of reference indicate like parts.

The nature of this invention consists in machinery for bending scythe-snaths, whereby the work is more rapidly and economically performed than by the ordinary method of bending them by hand. The machinery for accomplishing this object is a combination of a series of followers or pressers, which are made to move in concert with each other, to bear simultaneously upon both sides and all parts of a stick of ash, or other suitable timber, to bend it into the required curves for forming a scythe-snath, which movement of the shaping-pressers is produced by a corresponding series of cams acting on each, and so shaped and proportioned in size as to give faster and slower motion to the shaping-pressers, and move them a lesser or greater distance, according to the depth of the curve in the snath from a longitudinal centre line and the distance therefrom which each presser would have at the point of contact with the stick being bent. Connected with the shaping apparatus are also arrangements for releasing the bent snath and removing it from the machine, as hereinafter described.

A represents a rectangular frame, built of strong timbers. At the upper part of the frame is a series of cams, B B, placed on a shaft, a , running from side to side. The cams have various curves on their peripheries, and are of different sizes, no two of them being exactly alike, and are so formed as to move the horizontal followers or shaping-pressers b b exactly according to the shape of the curve in the snath at the point acted upon by each presser. The pressers are connected with the cams by a hook, c , on the end of each, which catches in a rim on the periphery of the cams, by which hook the cam draws the pressers back. Some of the pressers b b have single heads d , and others are coupled together in pairs by heads e , which heads are severally faced in the shape required for bending the snath at the parts they touch, respectively. The pressers b b are connected by straps g g with corresponding pressers b' b' , having corresponding heads d' e' , the heads e e' being loosely coupled with the pressers and pivoted to the connecting-straps in such manner that they can play freely, and by the movement of the pressers have their faces brought nearly in a straight line, to admit a straight stick of timber, or be arranged relatively to each other in the desired curves for bending the snath, while the distance between the heads remains unchanged. The heads e e' on one side are connected by a sheet-metal strap, i , that lies against the face of the intermediate heads d d . The opposite central heads d and d' are connected by a cross-rod, h , fig. 3, which is acted upon, to move then in concert, by a taper-lever, k , that rises and falls on the head of a stud, k' , with each movement back and forth of the pressers, which arrangement may be applied to other opposite pressers, to connect them in their movements, instead of the straps g . The shaping-pressers all rest on beams across the frame, and the heads lie upon a thick board, C, that is slotted from end to end, in the curve of the snath, directly under the space between the heads of the pressers when the snath is completely bent. The cam-shaft a is turned by a hand-lever, l , at one end. When the pressers b b are drawn back, as shown in fig. 1, the space between the heads is straight enough to admit the stick to be bent, which stick, when hot by steaming, is introduced end-wise and lies in the space aforesaid. On each end of the machine are hung two side-clamping levers D D, one of which is thrown open to introduce the stick, and is then hooked, like the other, to a rope or chain, m , which is wound upon the shaft a , to draw them up against the ends of the stick and clamp it lengthwise at the same time the pressers are moved up to bend the snath laterally. Placed over the heads of the pressers is a frame, E, fig. 3, on the under side of which are fastened vertical followers n n , whose ends are ranged directly over the space occupied by the snath when bent, and are moved down by racks and pinions p p' on each end of the frame E, for the purpose of pushing the snath out of the space between the heads of the pressers down through the slot in the board C into an iron mould, r , that is placed in a double clamp, F, mounted

on trucks w , which stand on a train-way, q q , to be run out with the snath. The clamps F are opened to take out the mould r , which holds the snath till it is cold and set. Many such moulds are required for business.

The machine can be operated by hand or power, and modifications may be made in the arrangement of the machinery without departing from the principles of operation of my invention; and therefore I do not confine my claims to the particular devices and their arrangements herein described; but having fully described my invention and the means of performing it, what I claim as new, and desire to secure by Letters Patent, is—

1. The connected pressers b and b' , with their heads d and d' , e and e' , arranged as described, and operated upon by cams B , or their equivalents, so as to be moved in concert for receiving a straight stick between them and bending it into shape for a scythe-snath, substantially as herein described.

2. The sliding-frame E , with vertical followers n , constructed and arranged substantially as and for the purposes herein specified.

3. The double clamp F , in combination with the iron mould r , arranged and operating substantially as and for the purposes herein set forth.

4. The combination of the cams B , the pressers b b' , the followers n , and the lever-clamps D , constructed, arranged, and operating in the manner and for the purposes herein described.
